INVENTOR
PHILIP W. TOMPKINS

BY Chas. E. Townsend
ATTY.

UNITED STATES PATENT OFFICE.

PHILIP W. TOMPKINS, OF SAN FRANCISCO, CALIFORNIA.

LIQUID SAMPLER.

Application filed May 4, 1921. Serial No. 466,838.

To all whom it may concern:

Be it known that I, PHILIP W. TOMPKINS, a citizen of the United States, residing at San Francisco, in the county of San Francisco and State of California, have invented new and useful Improvements in Liquid Samplers, of which the following is a specification.

This invention relates to a liquid sampler. 10 It is the principal object of the present invention to provide a device by which liquids contained in storage tanks and tank cars may be proportionately sampled irrespective of the shape of the container, and 15 thus insuring that a representative "core" may be made accurately showing the condition of the liquid throughout the depth of the tank and in direct ratio to the shape of the container.

20 The present invention contemplates the use of a container adapted to be lowered to any desired depth within a body of liquid, and which may be automatically closed and withdrawn from the liquid at a desired 25 depth, entrapping a volume of liquid at the exact depth desired.

The invention is illustrated by way of example in the accompanying drawings, in which:

30 Figure 1 is a view in vertical section and elevation showing one form of the present invention.

Fig. 2 is a view in vertical section and elevation showing a second form of the invention.

35 Referring more particularly to the drawings, 10 indicates a tubular container. The lower end of this container is provided with a ring 11, externally threaded to receive a 40 valve cap 12. This cap is formed with a central opening 13 having a tapered valve seat around the marginal edge thereof. A freely moving valve member 14 normally rests by gravity upon this seat and is fitted 45 with a stem 15 extending upwardly within the case 10. A pair of guide spiders 16 are secured across the case 10 and serve to centralize the stem 15 and the valve member. The valve member 14 is formed with a con- 50 vexed back portion which will assume the position indicated by dotted lines when the valve is raised. This will form an annular throat 17 between the back of the valve and the casing 10. The area of this throat is 55 computed to accurately agree with the area of the opening 13, thus making it possible

for liquid to freely pass around the valve member at the same rate that it flows into the casing 10, through the opening 13. The sectional area of the casing 10 is also calculated to substantially agree with the areas of the throat 17 and the opening 13. This will insure that the volume of liquid flowing through the container will be identical in consistency with liquid upon the outside 60 of the container at the same level. 65

The upper end of the casing 10 is normally opened and is fitted with a trap valve 18. This member is in the form of a flat plate hinged to one side of the casing on a pin 19 carried by a hinge leaf 20. The weight of this valve is such that downward movement of the sampler through a liquid will lift the valve while bringing the sampler to rest or raising the same will instantly close this member and partially determine the sample of liquid obtained, the upward movement of the trap being limited by a stop 21. 70 75

Longitudinally extending fins 22 are secured around the outer circumference of the casing 10. These fins tend to hold the sampler in a vertically aligned position as it travels through the liquid. Two of the fins are formed with perforations 28 receiving the eyes of a bail wire 29. This wire is looped at its center to form an eye 30 receiving a suitable cord as shown in the drawings. The cord of course may be noted or otherwise marked, so that the depth to 80 85 which the sampler is lowered may be conveniently determined.

Reference being had to Fig. 2 of the drawings, it will be seen that the casing 10 is straight throughout its length and does not flare at the bottom as shown in Fig. 1. The lower end of this casing is threaded to receive the valve cap 12 having a central opening 13. Valve member 31 is adapted to register with the valve seat of the opening 13. 90 This valve member is secured to the lower end of a cylindrical and tubular stem 32. The stem extends substantially the length of the casing 10 and is held centrally therein by ears 33. These members permit the stem 95 with its valve to move longitudinally of the casing while insuring that a uniform annular passageway 34 will be formed between the stem and the casing. The sectional area 100 of the opening 13 and the sectional area of the annular passageway 34 agree so that the lowering of the sampler will be accompanied 105 110

2
by a continuous flow of the liquid through the opening 13 and into the passageway 34. As this flow is not restricted the liquid within in the passageway 34 will assume the same level as identical liquid on the outside of the sampler. This form of the invention is likewise provided with the trap valve previously described, the directing fins 22 and the bail 29.

10 In operation of the form of the invention shown in Fig. 1, the sampler is secured to a cord or rod and lowered to a desired level. As the device descends through the liquid the valve member 14 will raise from 15 its seat to a position determined by the lowermost spider 16 and the trap valve 18 will swing to its uppermost position. When a desired level has been reached the sampler is brought to rest. At such a time the valve member 14 will settle by gravity and the weight of the trap valve 18 will cause it to close. Substantially the same action takes 20 place in the operation of the form of the invention shown in Fig. 2, upward movement 25 of the valve structure being limited by an inwardly extending flange 35 at the top of the casing 10. When a "core" is to be made representing the contents of a tank from top to bottom and consequently in unequal proportions, the sampler is used to take as much 30 material from any section of the tank independently of any other section as is necessary to procure a sample in direct ratio to the shaping of the tank. For example, the 35 number of 10 inch samples for practical representation of the contents of a 78 inch standard 8,000 gallon tank car is as follows:

		Samplers full.
40	Bottom 10"	1
	2nd 10"	1
	3rd 10"	2
	4th 10"	2
45	5th 10"	2
	6th 10"	2
	7th 10"	2
50	Top portion	1
		13

Where large storage tanks are involved the use of this device enables a sample to be taken at various positions in the tank, as for instance in the different corners, or a sample may be taken directly from the bottom of the tank to determine the depth of the settling without interfering with the superstratum of liquid.

It will thus be seen that the device here disclosed, while decidedly simple in construction and operation, insures that the contents of a liquid container may be accurately determined without unduly agitating the liquid, while accurately withdrawing liquid from a desired depth in the container.

While I have shown the preferred form of my invention as now known to me, it will be understood that various changes might be made in the combination, construction and arrangement of parts by those skilled in the art, without departing from the spirit of the invention, as claimed.

Having thus described my invention, what I claim and desire to secure by Letters Patent is:

1. A device of the character described comprising a receptacle having valve openings at the top and bottom thereof, valve members cooperating with said openings and adapted to open as the receptacle is lowered through a liquid and to simultaneously close when the device is brought to rest within the liquid, the unoccupied space in said receptacle around the lower valve when it is open being of a cross-sectional area equal to the cross-sectional area of the bottom valve opening.

2. A device of the character described comprising a tubular casing, a normally opened valve permitting liquid to pass outwardly from the top of the casing, valve means in the bottom of the casing normally opened to permit liquid to flow into the casing in volume such as to cause the liquid within the casing to stand at the same level with the liquid at the outside of the casing, and means whereby both of the valves will be closed when the casing comes to rest within a liquid or is elevated therefrom.

3. A device of the character described comprising a tubular casing, a bail connected with the top thereof and adapted to suspend the same in a vertically aligned position, a hinge valve at the top of said casing adapted to open as the casing is lowered in a liquid, a gravity operated valve at the bottom of said casing adapted to open as the casing is lowered and to close when the device comes to rest, and means for insuring that the volume of liquid entrapped within the device will accurately represent the liquid as it stands at the point where the device is arrested on its downward course of travel.

PHILIP W. TOMPKINS.
